E. E. HALE

COLLAPSIBLE BOX

Filed Aug. 15, 1927

INVENTOR
EDWARD E. HALE

UNITED STATES PATENT OFFICE.

EDWARD EVERETT HALE, OF BUFFALO, NEW YORK.

COLLAPSIBLE BOX.

Application filed August 15, 1927. Serial No. 213,127.

My invention relates to improvements in cardboard boxes and the object of the invention is to construct a collapsible box of the telescopic type in which the two parts which constitute the box and the lid are each formed from single blanks of material which are suitably cut, so that they can be readily bent and locked in position to form the box when required.

10 A further object of my invention is to so construct my box that it is locked together at the corners in such a manner that a comparatively rigid construction is obtained which will not readily distort and damage 15 fragile articles such as flowers which may be placed therein. A further object of my invention is to so form my blanks that they are of rectangular form, which will thus permit them to be cut from sheets of material 20 without any waste of stock.

My invention consists of a cardboard box constructed and arranged as hereinafter more particularly described and illustrated in the accompanying drawing, in which:—

25 Fig. 1 is a plan view of the cut blank from which my box is formed.

Fig. 2 is a perspective view of a fragmentary portion of my box showing two of the adjacent sides partially bent to form one 30 corner.

Fig. 3 is a similar view to Fig. 2, showing the sides brought together to form the corner, the locking tongue therefor being in the unlocked position.

35 Fig. 4 is a similar view to Figs. 2 and 3 showing the box corner in its final form and the locking tongue in the locked position.

Fig. 5 is a perspective view of the box formed from the blank illustrated in Fig. 1.

40 Like characters of reference indicate corresponding parts in different views.

As my box is of the telescopic type, the lower and lid portions are of course of the same form, the lid portion being, however, 45 slightly larger than the lower portion in order that it may fit thereover, and it will therefore be only necessary to describe one of the two portions of the box.

1 is the bottom of the box which is of rectangular form and bent upwardly along its 50 four edges 2, 3, 4, 5, to form the sidewalls 6, 7, 8 and 9 as illustrated in Fig. 1. In this figure the full lines show where the blank is cut and the dotted lines where it is bent.

55 The blank is of rectangular form and as it includes the rectangular bottom 1 and the

rectangular sides 6—9, it also includes the square corner members 10, which are utilized to form the corner locking means. Such portions being cut and bent in the following manner:

The inner edges of the members 10 are of course in alignment with the edges of the bottom 1, the edges 11 and 12 thereof being in alignment with the edges 3 and 5 of the bottom and the edges 13 and 14 being in alignment with the edges 2 and 4 of the bottom. Extending inwardly along the line of the edges 11 and 12, I cut slots 15, which each terminate in a cross slot 16 which is provided to prevent any possibility of such slots 15 tearing when the box is being formed from the blank. The sides 13 and 14 of the members 10 are also provided with slots 17 which extend from the inner corners of the members outwardly for a distance substantially equal to the distance from the inner ends of the slots 15 to the inner corners of the members. The corner members are also cut diagonally by slots 18 which extend from their inner to outer corners, and bending lines 19 are also provided in the corner members and extend from the ends of the slots 17 to the diagonal cuts 18 and lie substantially parallel to the edges 3 and 5 of the bottom 1. Slots 20 are also furnished at the outer ends of the slots 17 for preventing tearage when the box is being formed.

My box blanks are designed to be shipped to the user in flat form as illustrated in Fig. 1 and when he desires to use a box it is only necessary for him to fold a pair of bottom and top forming blanks in the following manner.

The triangular portions 20 and 21 formed by the diagonal cuts 18 in the corner members are first folded upwardly along the bending lines 12 and 14, and the side members 6, 7, 8 and 9 are then folded upwardly along the bending lines 2, 3, 4 and 5 until the corners substantially assume the form illustrated in Fig. 2, the triangular tongues 22, each bounded by the slots 17, 18 and the bending line 19 being bent back upon the respective triangular portions 20 as shown in this figure. The sides 6 and 8 are first swung into the vertical position, so that the triangular members 21 lie in alignment with and above the edges 3 and 5 of the bottom. The sides 7 and 9 are then swung upwardly into the vertical position and as the slots 17 from which the tongues 22 are bent back are of the same length as the distance from the corner to the inner ends of

the slots 15. The tongue containing bent triangular members 20 will pass through the respective slots 15 in the manner illustrated in Figs. 2 and 3. When this is done, the tongues 5 22 will be in the position illustrated in the Fig. 3 and to lock the corners it is only necessary to bend such tongues downwardly into the position illustrated in Fig. 4 wherein their free edges 23 formed by the slots 17 will engage the bent edges 11 and 12 of the corners formed between the sides 6 and 8, and the respective triangular members 21.

From the foregoing description it will be apparent that I have devised a simply constructed collapsible box which can be used for a variety of purposes and in which I have obviated the use of adhesives, wire clips or other locking means, the box being securely held in its adjusted form by means of integrally formed locking tongues which answer the dual purposes of providing a means for securely locking the carton in its adjusted form and also providing a means for substantially strengthening the corners and thus preventing distortion of the box and injury to any fragile articles which may be contained therein.

What I claim as my invention is:—

In a corner locking structure for collapsible boxes, the combination of the bottom and two adjacent sidewalls of integral triangular corner locking members formed upon the ends of the sides and bent at right angles thereto and having slots extending along the lines about which they are bent, one of said slots extending upwardly from the bottom of the corner along the bending line of one triangular corner locking member, the other slot extending downwardly from the top of the corner along the bending line of the other triangular corner locking member, and a bending line extending across the triangular member having the upwardly extending slot from the top of such slot to one of the free edges of such member, a tongue member formed by the slot and said free edge in said locking member and adapted to be bent back upon its corner locking member along the bending line so that it enters the slot in the other corner locking member when the corner is being formed, a means whereby the returning of the tongue to its original unbent position constitutes a corner retaining lock.

EDWARD EVERETT HALE.
